UNITED STATES PATENT OFFICE

2,234,740

REFRIGERATING APPARATUS

George C. Pearce, Dayton, Ohio, assignor to General Motors Corporation, Dayton, Ohio, a corporation of Delaware

Application January 30, 1934, Serial No. 708,993

21 Claims. (Cl. 200—83)

This invention relates to refrigerating apparatus and more particularly to the control mechanism therefor.

In domestic refrigerators it has been customary to provide a single evaporator which is employed for cooling the interior of the food compartment as well as for freezing ice cubes and comestibles. In order to serve this dual purpose, the temperature of the evaporating means is necessarily something of a compromise. In order to freeze ice cubes and comestibles, it is necessary to operate the refrigerating system at freezing temperatures. This causes moisture to condense and collect upon the evaporator or cooling unit in the form of frost. This frost acts as an insulator and prevents the efficient transfer of heat between the food compartment air and the evaporator.

It has been customary to instruct the user of a refrigerator to periodically shut down the refrigerating apparatus in order to permit the frost to melt from the cooling unit. This, however, is rather inconvenient and if not carefully attended, the refrigerating apparatus may be kept shut down for too long a time, thus permitting the temperatures within the food compartment to rise sufficiently high to permit food spoilage.

It is an object of my invention to provide a refrigerating apparatus wherein a common control means is provided for continuous cycling of the refrigerating apparatus to maintain the evaporating means either at freezing temperatures or temperatures sufficiently high to permit defrosting of the evaporator and yet provide adequate cooling of the food compartment so as to prevent food spoilage.

It is a further object of my invention to provide a refrigerating system having a control means for cycling the refrigerator between given high and low limits which is further provided with an adjusting means operated by a single knob and dial which, under the control of the knob, will provide cycling at other temperature limits below freezing with the differential between the high and low limits remaining the same, as well as means under the control of the knob for providing continuous cycling with the differential between the high and low limits widened and with the upper limit being a sufficient amount above freezing to cause defrosting of the evaporator or cooling unit and to permit continuous cycling of the refrigerating system without the collection of frost.

It is another object of my invention to pro-

vide a means controlled by such a knob at shut off the refrigerating system.

Further objects and advantages of the present invention will be apparent from the following description, reference being had to the accompanying drawings, wherein a preferred form of the present invention is clearly shown.

In the drawings:

Fig. 1 is a diagrammatical view of a refrigerating system illustrating my invention;

Fig. 2 is a vertical secondary view of a refrigerator cabinet showing a portion of the control means for the refrigerating apparatus with the control knob in No. 1 position;

Fig. 3 is a top view of a portion of the control apparatus shown in Fig. 2 but with the control knob in "off" position;

Fig. 4 is a front view partly in section of the control apparatus shown in Figs. 2 and 3 but with the control knob in "off" position;

Fig. 5 is a sectional view along the line 5—5 of Fig. 3;

Fig. 6 is a sectional view along the line 6—6 of Fig. 3;

Fig. 7 is a top view of a modified form of control means with the temperature adjusting mechanism and the control knob in No. 1 position and the switch contacts in closed position;

Fig. 8 is a front view of the modification shown in Fig. 7;

Fig. 9 is a sectional view along the line 9—9 of Fig. 7;

Fig. 10 is a fragmentary top view similar to Fig. 7 excepting that the switch contacts are shown in open position and the temperature adjusting mechanism is shown in No. 4 position;

Fig. 11 is a sectional view along the line 11—11 of Fig. 7 showing the control knob and adjusting means in No. 1 position; and

Fig. 12 is a sectional view along the line 11—11 with the control knob and adjusting means in No. 4 position.

Referring to the drawings and more particularly to Fig. 1, there is shown a refrigerating apparatus including a compressor 20 for compressing the refrigerant and for forwarding the compressed refrigerant through a supply conduit 21 to a condenser 22 where the compressed refrigerant is liquefied and collected in a receiver 23. From the receiver 23 the liquid refrigerant is forwarded through a supply conduit under the control of a suitable expansion valve 24 to an evaporator 25 located within the food compartment 26 provided with means for freezing ice cubes or comestibles within an ice tray 27. frigerant within the evaporator 25 evaporates under reduced pressure and absorbs heat from the ice trays and from the air in the food compartment. This vaporized refrigerant is returned to the compressor through a return conduit 28.

The compressor is driven by an electric motor 29 under the control of a control means, generally designated by the reference character 30 and illustrated diagrammatically in Fig. 1. This control means comprises a thermostat bulb 31 in contact with portion of the evaporating means and provided with a volatile liquid or refrigerant. The thermostatic bulb, although placed in contact with the evaporating means, follows the temperature of the food compartment as well as the temperature of the evaporating means since the temperature evaporating means follows the temperature of the food compartment and since the bulb is exposed to the food compartment air. The thermostat bulb 31 is connected by tubing 32 to a metal bellows 33 which through snap acting mechanism opens and closes a set of switch contacts 34 located in one of the supply conductors 35 of the electric motor 29. In series with the supply conductor 35 and the switch contacts 34 is an overload protecting mechanism comprising a set of switch contacts 36, an electric heater 37 in series with the contacts 34 and 36 and a bimetal trip mechanism 38 for opening the contacts 36 under the influence of the predetermined amount of heat from the heater 37. The control means 30 operates to maintain the proper temperature of the evaporating means and the food compartment.

Referring now more particularly to Figs. 2 to 6 inclusive, for further illustration of one embodiment of my invention, there is disclosed a supporting platform 40 provided with supporting legs 41 resting upon a removable partition wall 42 forming the top wall of the food compartment 43. Extending downwardly from the platform 40 is a tubular shaft 44 which extends downwardly through the removable wall structure 42 which is provided with rubber sealing gaskets 45 for preventing leakage of air and moisture between the food compartment and the machinery compartment 46 within which the control means is located. The lower end of the tubular shaft is provided with a rotatable manual control knob 47 or manipulator 47 which is provided with indications "off" and "6" which are clearly shown in Fig. 2, as well as the indications "1" to "5" inclusive which extend around the other side of the control knob between the designations "off" and "6." As viewed in Fig. 2, the control knob or manipulator, as well as the control apparatus, is shown in No. 1 position.

Within the hollow shaft 44 there is provided a rod 48 provided with a red control button 49 at its lower end which serves to reset the overload means and serves as an indicator when the overload means has tripped by dropping downwardly from this position shown in Fig. 2 so that it is clearly visible and clearly indicates the tripping of the overload means.

Referring now more particularly to Fig. 4, the upper end of the hollow shaft 44 is shown provided with a bushing 50 which is rotatably mounted within an aperture in the platform 40. This bushing is provided with flanges which extend on either side of the platform 40 so as to permit rotation of the bushing 50 but to prevent vertical movement thereof. The bushing 50 is fixed to the hollow shaft 44 by a set screw 51. The overload control rod 48 extends upwardly through the

bushing 50 and is connected by a pin and set screw 52 at its upper end to a lever 53 which is pivoted upon a screw 54 to a vertical bracket 55. This vertical bracket 55 at its upper end is pivotally connected by a pin 56 to a contact lever 56 carrying a contact 57 which cooperates with a spring mounted contact 58 corresponding to the set of contacts 36 to open and close the electric motor circuit. This contact lever 56 is normally held in closed position by a bimetal strip 59 which is adapted to be heated upon an overload by a nickel chromium wire heater 60 connected in series with the contacts 57 and 58.

At its lower end the bimetal strip 59 is connected to a pivot block 61 to which is also connected a bimetal compensating strip 62 which is held by an adjusting screw 63 and a spring 64 at its free end and thus serves as an adjusting means. This bimetal strip 61 also acts as a temperature compensator for the bimetal strip 59 for compensating the bimetal strip 59 for the variations in room, and particularly the machine compartment, temperature. The lever 53 is provided with an insulating portion 65 having pins 66 projecting therefrom on either side of the contact lever 56, which supports the lever 53 and the rod 48 when the contacts 57 and 58 are in closed position. Should an excessive amount of current pass through the heater 60, the bimetal strip 59 will bow to the left as shown in Fig. 4, so that its upper end moves out from under the lever 56 and permits it to fall. This contact lever 56 is thus permitted to fall and the rod 48 falls with it displaying the red button 49 within the food compartment 43. In order to reset the thermal overload mechanism, the button 49 is pushed upwardly thus causing one of the pins 66 to raise the contact lever 56 to permit the bimetal strip 59 to resume its vertical position beneath the contact lever 56. The projection of this insulating portion which carries the pins 66, during this time, engages the projecting end of the leaf spring carrying the contact 58 and holds the overload contacts open to prevent forcible operation of the apparatus under overload conditions.

The upper end of the bushing 50 is threaded and provided with a thin nut 70 which is held from rotation by a hook-shaped member 71 whose vertical portion holds one of the flats of the hexagonal nut 70. The hook-shaped member 71 is provided with the apertures 72 and 73 which receive an arm 74 extending from a top plate 75 provided with ears 76 pivotally connected by a pin 77 to a bracket 78 which extends upwardly from the metal platform 40. Resting upon the bottom portion of the bracket 78 is a metal bellows 79 corresponding to the bellows 33 of Fig. 1 fastened to the platform 40 by a nut 80 and connected to a thermostat bulb, such as bulb 31, by a tube 81 which corresponds to the tube 32.

At the upper movable end of the bellows there is provided a conical pin 82 which is seated within the recess in the bottom side of a bellows follower 83 provided with ears which are pivotally connected to the bracket 78 by the pin 84. Seated upon the bellows follower 83 is a lower spring retainer 85 having a conical-pointed lower end which seats in a recess upon the top of the bellows follower 83. This lower spring retainer 85 supports the lower end of a compression type coil spring 86 whose upper end is retained by an adjustable upper spring retainer 87 which is threaded upon a pin 88 riveted to the top plate 75 to vary the initial tension of the spring 86. This

provides the ordinary factory-set range adjustment.

When the control knob or manipulator 47 is turned, the thin nut 70 moves up and down upon the threaded portion of the upper end of the bushing 50 to permit raising or lowering of the hook-shaped member 71 and the free end of the top plate and upper spring retainer 87 so as to vary the tension upon the spring 86 in order to control the expansion of the metal bellows 79.

Also pivotally mounted upon the pivot pin 84 is the main switch arm or lever 90 which at its free end has an insulating member 94 fastened thereto by a bolt 96. This insulating member is provided with V-shaped notches 95 which receive knife edges at the ends of a wish-bone shaped member 97 which is provided with a rubber silencer 98 which cooperates with stop portions 99 formed on a bracket 100 fixed to the platform 40. These stop portions 99 are provided with tripping pins 101 which contact the wish-bone shaped member immediately before tripping in order to control its tripping position. The wish-bone shaped member is connected at its closed end to a tension coil spring 102 which is connected at its opposite end to an upstanding projection 103 formed on a contact lever 104 carrying a movable contact 105 which cooperates with a stationary contact 106, which set of contacts corresponds to the set of contacts 34 shown in Fig. 1. This contact lever is pivoted at 107 to the bracket 100. The insulating member 94 insulates the control knob, the bellows, and the remainder of the refrigerating system from the current carrying contact lever 104.

The main switch arm or lever 90 is operated by the metal bellows 79 and the bellows follower 83 through a resilient connection which includes a hook-shaped member 108 which hooks the bottom 40 of a main switch lever 90 and which extends upwardly through an aperture in the extension 109 of the bellows follower 83 upon which rests a small compression type coil spring 110 which surrounds the upper end of the hook-shaped member 108. The upper end of the spring 110 is held by a cotter pin 111 which extends through the upper end of the hook-shaped member 108 and yieldingly connects the contact arm 90 with the bellows follower 83 through an extension 109. At the opposite side the main switch lever or arm 90 is provided with a downward extension 91 which is adapted to be engaged by a projecting foot 92 extending from the bushing 50 when the control knob or manipulator 47 is turned to the "off" position. When this projecting foot 92 comes into engagement with the downward projection 91, the main switch arm 90 is forcibly moved downwardly and held in the "off" position, thus holding the main switch contacts 105 and 60 106 in the open position. The resilient connection between the main switch arm 90 and the bellows follower under these conditions yields and prevents excessive strain upon the switch arm 90 by permitting the bellows follower 83 to move 65 upwardly without a corresponding movement of the main switch arm 90.

The bushing 50 is also provided with a cam 115 which when the control knob is in No. 1 position cooperates with the end of a lever 116 70 pivoted at an intermediate point to an upwardly extending portion 117 of the bracket 78. The opposite end of this lever is connected to a tension type coil spring 118 which has its upper end connected to an eyelet at the lower end of a pin 120 which extends through an aperture in

the bellows follower 83 and has its upper end threaded into a sleeve 121 provided with a hexagonal head 122. This sleeve, which is pulled downwardly by the tension spring 118, is adapted to rest upon the bellows follower when the main switch arm 90 and the bellows follower are in the upper portion of their normal movement but to be separated from the bellows follower as shown in Fig. 5 when the main switch arm 90 and the bellows follower 83 are in the lower portion of their normal movement. When the bellows follower and the main switch arm 90 are in their lower positions, the hexagonal head 122 is pulled down upon, and is adapted to rest upon the seat 123 provided with an aperture which receives the sleeve 121. This seat 123 is formed from an upwardly projecting portion of the bracket 78. A set screw 124 extends into the hexagonal head 122 and serves to lock the threaded pin 120 within the sleeve 121.

This mechanism provides the differential adjustment for the switch. By turning the sleeve 121 by means of its hexagonal head 122 upon the threaded pin 120 the tension of the differential spring 118 is correspondingly varied. Inasmuch as this spring affects only the upward movement of the bellows it provides a means for varying the pressure and temperature limits between the opening and closing of the switch contacts 105 and 106 and constitutes the ordinary 30 factory-set differential adjustment. This differential adjustment affects only the closing pressure and temperature by increasing the tension upon the spring 118, the open temperature and pressure limit for closing pressure and temperature limit is increased without affecting the lower temperature limit.

The opening and closing temperatures of the switch are also controlled by the control knob which through the medium of the partially 40 threaded end portion of the bushing 50 and the thin nut 70 and the compression spring 86 provide a limited range adjustment in addition to the factory-set range adjustment which beginning with No. 6 position and turning the knob toward No. 1 position raises both the upper and lower temperature limits approximately the same amount, for example about 2° or 3° F., but in the No. 1 position of the control knob, the cam 115 also comes into play as previously described and 45 through the medium of the lever 116 provides an additional tension upon the differential spring 118 which further raises the upper temperature limit. In this position therefore the differential between the upper and lower temperature limits 55 is widened as well as both temperature limits being raised.

The upper temperature limit in No. 1 position is preferably made sufficiently high so as to insure defrosting during each cycle, while the lower 60 temperature limit is made sufficiently low to insure adequate cooling of the food compartment to prevent food spoilage. For example, a cut-in temperature of 40° F. and a cut-off temperature of 14° F. may be provided in No. 1 position, while 65 in No. 2 position the cut in temperature might be set at 28° F. and cut off temperature at 11° F. In positions 3 to 6 inclusive, both the cut in and cut off temperatures may be lowered about 3° F. for each different position. The positions numbered 2 to 6 are employed to obtain freezing temperatures for freezing ice and comestibles.

As explained before, when the control knob is turned to "off" position, the foot 92 engages the extension 91 of the main switch arm 90 in order 75

to forcibly open the main switch contacts and to hold them in this position against the tension of the yielding connections provided by the hook-shaped member 108 and the spring 110. It may be noted that during this time the lever 116 remains upon the cam 115 but is not effective while the control knob is in the "off" position since the movement of the main switch arm is prevented.

In Figs. 7 to 12 inclusive I have shown a modification of my invention. In this modification I have provided a flat, rectangular base 150 of insulating material to which is attached by means of the screw 151 a bellows supporting bracket 152 which has a flange 153 at one end provided with a notch 154 for supporting the fixed end of the metal bellows 155 which is connected to a tube 156 which connects with the thermostat mounted upon the evaporator or cooling unit. The opposite end of the bracket 152 is provided with an up-turned flange 157 which is adapted to be engaged when the bellows is extended or expanded an excessive amount by a cap 158 seated upon the movable end of the bellows. Extending from the cap 158 is a rod 159 which is provided with a shoulder 160 and a reduced portion 161 having a threaded end.

A pin 162 extends through the rod 159 and is received within a notch 163 formed in the main switch lever or arm 164 which is pivoted upon a pivot screw 165 supported by a pivot bracket 166. The main switch arm 164 is held against the pin 162 by a compression type coil spring 167 which extends between the cap 158 and a spring retainer 168 which seats upon the main switch arm 164. The main switch arm 164 has a long upper portion 169, clearly shown in Fig. 7, and a short lower portion 170 which is parallel to the upper portion 169 and connected thereto by a web 171. The long upper portion of the switch arm 164 is provided with an insulating block 172 at its free end which is provided with V-shaped notches 173 which receive a pair of knife edges formed upon the legs of a wish-bone shaped secondary lever 174 whose movement is controlled and limited by the pair of stop pins 175 which are fixed to an adjusting member connected to the base 150. This adjusting member varies the distance between the upper ends of the stop pins in order to provide a factory-set differential adjustment. The closed end of the wish-bone shaped secondary lever is connected by a tension spring 176 to an irregularly shaped contact arm 177 which is pivoted to the base upon a pin 178. The contact arm 177 carries a contact 179 which cooperates with a stationary contact 180 which is fastened to the base by a screw 181. The insulating block 172 serves to insulate the bellows, the arm 169, the manual controls, and the remainder of the refrigerating system from the current carrying portion of the switch.

As the pressure within the bellows increases, corresponding to an increase in temperature within the food compartment and the evaporator, the bellows will expand thus moving the switch arm 164 to the position shown in Fig. 7 causing the main switch contacts 179 and 180 to be closed. When the temperature within the food compartment and the evaporator is lowered the metal bellows 155 will contract thus moving the main switch arm 164 to the position shown in Fig. 10 thereby tripping the secondary lever 174 and the toggle spring 176 to the position shown in Fig. 10 so as to cause the main switch contacts 180 and 179 to be separated to open the circuit to the compressor motor.

In order to prevent an excessive flow of current from damaging the motor, I provide a thermal overload means having contacts in series with the main switch contacts 179 and 180 for opening the electric motor circuit when the dangerous flow of electric energy flows to the electric motor. This mechanism includes a bracket 185 mounted upon the base and carrying a spring brass strip 186 at its upper end which is fastened at one end by a screw 187. This brass strip carries a contact 188 at its free end which cooperates with a second contact 189 mounted upon the end of a second brass strip 190 fastened by a screw 191 to a second bracket 192 fastened to a base. The bracket 192 is connected to a source of electricity 15 by a screw 193 which serves as a binding post.

Extending to the right of the screw 193 as shown in Figs. 7 and 8, is a bimetal strip 194 which has its opposite end adjustably held in a flanged nut 195 and a lock nut 196 upon a stud 197 fixed to the base 150. The other end of the bimetal strip 194 is connected to a rotatable round insulating member 198 which is formed with flats at either end to which a bimetal strip 194 and a second bi-metal strip 200 is fastened by rivets. The bimetal strip 194 serves an adjusting means and a means for compensating the second bimetal strip 200 for changes in machine compartment and room temperature. The second bimetal strip 200 is similar to the bimetal strip 194 but is provided on its bottom side with a serpentine heater wire 201 which is riveted thereto at one end and connected to the screw 185 to the base 150.

The free end of this second bimetal strip serves as a latch which normally holds the lower end of an insulating bell crank lever 203 from rotating in a clockwise direction about its pivot bolt 204 under the influence of the tension coil spring 205 which has one end connected to an ear at the lower end of the insulating bell crank lever 203 and its opposite end connected to an ear extending from the jacket 192. The other end of the bell crank lever is provided with a knob 206 which is held upon the top of the brass strip 186 immediately above the contacts 188 and 189 by the second bimetal strip 200 so as to hold the contacts 189 and 188 in closed position.

This overload mechanism provides a circuit 50 from the bracket 192 through the brass strip 186, the contacts 189 and 188, the brass strip 186, the bracket 185, and then through the serpentine wire heater to the second brass strip and is then conducted through a flexible electrical conductor 207 to the contact arm 177 which carries the contact 179 which cooperates with a stationary contact 180. When a dangerous or excessive flow of electric current passes through this circuit the wire heater 201 heats the second bimetal strip 200 sufficiently to cause it to bow downwardly and release the bell crank lever 203 which rotates in a clockwise direction under the influence of the spring 205 so as to raise the knob 206 from the brass strip 186 to permit the contact 188 to move upwardly away from the contact 189. The brass strip 186 springs upwardly further than the brass strip 190 thus causing the contacts 188 and 189 to be separated. The release of the bell crank lever 203 by the bimetal strip 200 permits this lever to be rotated clockwise under the influence of the spring 205 and causes this lever to engage a pin 209 upon a T-shaped lever 210 also pivoted on the bolt 204.

At its opposite end this T-shaped lever 210 is 75

adjustably connected to a vertical rod 211 which extends downwardly through a hollow shaft 212 which extends from the machine compartment 215 in which the switch is located down through 5 the top wall 216 of the refrigerator cabinet. The top wall 216 is provided with a notch 217 within the food compartment 218 and within this notch 217 is a control knob 214 at the lower end of the hollow shaft 212. Within the control knob 214 is 10 a button 219 which is connected to the lower end of the rod 211. When the rod 211 drops, the button 219 also drops and exhibits a red band which indicates the fact that the overload mechanism has tripped.

15 The overload mechanism is restored to the normal closed position by pushing upwardly upon the button 219 which moves the rod 211 vertically. This moves the T-shaped lever 210 in a 20 counterclockwise direction which through the upper pin 209 rotates the bell crank lever 203 in a counter-clockwise direction about the pivot bolt 204 while the lower pin 208 bears upon free end of the brass strip 190 to hold the overload contacts 188 and 189 in open position during the 25 entire resetting operation. The counterclockwise movement of the bell crank lever 203 permits the bimetal strip 200 to return to its latched position in which the knob 206 holds the overload contacts in closed position.

30 The control knob 214 regulates the temperature of the evaporator and the food compartment by adjusting the operation of the metal bellows and the main switch contacts. The hollow shaft 212 upon which the control knob 214 is 35 mounted is provided with a flanged collar 220 at its upper end which is held within an aperture in a metal plate 221 fastened to the base 150. This connection between the collar 220 permits rotation of the hollow shaft 212 but prevents vertical 40 or axial movement thereof. The upper end of the hollow shaft 212 is provided with coarse threads 222 upon which is threaded a serrated nut 223 which is normally held from rotation by a coiled wire spring latch means 224 which is 45 adapted to engage in one of the notches provided in the periphery of the nut 223. This wire spring latch means is coiled around the pin 225 which is fixed in a bracket 227 pivoted to the metal plate 221. This spring latch means is prevented 50 from rotating about the pin 225 by the projecting end 226 which is hooked into the pivoted bracket 227.

The pivoted bracket 227 has a forked, humped end portion 228 which rests against the bottom side of the nut 223. By turning the control knob 214 and the cap 212, the nut 223 is moved upwardly or downwardly along the upper threaded portion 222 of the hollow shaft 212. Through its 55 forked end 228, the bracket 227 is pivoted about its pivot connection 229 with the metal plate 221. The pivoted bracket 227 has a second forked projection 230 which is provided with a pair of pins 231 which rest within depressions provided within 60 a spring retainer 232.

This spring retainer 232 supports one end of a rather stiff compression spring 233 which is supported at its other end by a second spring retainer 234 which is seated upon a shoulder 235 65 formed at the beginning of the reduced portion of the bellows rod 159 which is moved by the bellows 155. Within the heavy outer coil spring 233 is a light coil spring 236 which is held between an inner spring retainer 237 seated upon 70 the outer spring retainer 234 which in turn is

seated upon the shoulder 235 and a second inner spring retainer 238 which is normally seated upon a sleeve 239 which is threaded upon the threaded reduced portion of the bellows rod 159. The turning of the sleeve 239 upon the bellows rod 159 75 provides a factory-set differential adjustment. Normally this inner spring 236 is inactive or ineffective and moves bodily with the control rod 159 as shown best in Fig. 10.

However, when the control knob 214 is moved 10 to No. 1 position of the control knob 214, as shown in Fig. 11, the spring retainer 232 compresses the heavy coil spring 233 a proportionate amount and in so doing moves toward the bellows a sufficient distance to cause the nibs 240 15 which are formed thereon to engage the inner spring retainer 238 of the light inner spring 236 only upon the outward movement of the bellows 155 and the switch arm 164, thus providing an additional resistance to the expansion of the bellows 155 which raises the cut-in or closing temperature of the main switch contacts 179 and 180 in addition to the normal increase provided by the further compressing of the heavy outer spring 233. This additional resistance provided 20 in the No. 1 position by the light inner coil spring 236 thus widens the differential.

The upper limit or cut-in point of the refrigerating cycles in this control position is thus increased to about 40° F. which is sufficient to defrost the evaporator and yet the cut-out point remains at a relatively low point, about 14° F. This provides sufficient cooling of the food compartment to prevent food spoilage and yet permits the frost to melt from the cooling unit during each cycle. When the cold control knob is moved to positions 2 to 6 inclusive, the outer spring retainer 232 is progressively retracted and permits lower evaporator and box temperatures particularly for freezing purposes. In these positions the outer spring retainer 232 is sufficiently retracted so that the nibs 240 will not engage the spring retainer 238 within the normal range of movement of the bellows 155, the bellows rod 159, and the switch arm 164. This condition of operation is best illustrated in Fig. 12 in which the control knob 214 is shown in No. 4 position. Thus, when the control knob is in positions 2 to 6 inclusive, the light inner screw does not come into play and the switch operates with the differential 30 35 40 45 50 55 between the opening and closing of the switch contacts and the starting and stopping of the compressor remaining the same and this is, of course, called range adjustment.

The control knob 214 is also provided with an off position which controls the turning on and shutting off of the refrigerating system. In order to do this, the collar 220 is provided with a projection 242 which when the control knob is turned to "off" position engages the lower portion 170 of the switch arm 164 to forcibly move the switch arm 164 away from the pin 162 against the tension of the spring 167 in order to forcibly move the movable switch contact 179 to open circuit position and to hold it there as long as 60 65 desired.

In practice the switch and the refrigerating system are so set and adjusted as to provide the normal control in No. 2 position of the control knob to obtain fully adequate refrigerating temperatures for both the freezing of ice cubes and also for cooling the food compartment sufficiently to prevent food spoilage as has been customary in the past. The temperature in this position is sufficiently low to provide somewhat more than 70 75

the minimum requirement as to cooling of the food compartment and is also sufficiently low to freeze ice cubes and comestibles at a moderate rate. If quicker freezing or lower temperatures are desired, the control knob is adjusted or moved to one of the positions from 3 to 6 inclusive. When it is desired to defrost the evaporator, or to operate the evaporator at a temperature sufficiently high to prevent or retard the accumulation of frost upon the evaporator and to reduce the current consumption, the control knob is turned to No. 1 position which is just barely adequate or sometimes inadequate for ordinary freezing purposes, but which will supply sufficient refrigeration to the food compartment to prevent food spoilage. When the evaporating means is suitably constructed, the switch and the refrigerator may operate ordinarily in No. 1 position wherein any frost accumulating will melt from the evaporator every cycle. The evaporator may, of course, also be defrosted by moving the control knob to the "off" position to shut off the refrigerating system.

Thus I have provided a convenient control knob and thermal overload control which is accessible from the food compartment 218 and yet the switch mechanism is located within the machine compartment where it is not subject to the unfavorable moisture and freezing conditions present within the evaporator and food compartments. The control knob through its control of switch adjustment governs the continuous cycling of the refrigerating system to provide either temperatures sufficiently high to defrost the evaporator by a combined range and differential adjustment or by a limited range adjustment to provide lower evaporator and food compartment temperatures. In addition, the control knob serves to shut off the refrigerating system.

40 While the form of embodiment of the invention as herein disclosed constitutes a preferred form, it is to be understood that other forms might be adopted, all coming within the scope of the claims which follow.

45 What is claimed is as follows:

1. A switch including means for opening and closing an electric circuit, a bellows, a bellows follower operated by the bellows, said bellows follower having an insulating portion thereon provided with notches, and snap acting mechanism cooperating with said notches for actuating said first mentioned means.

2. A control switch including a pressure responsive means, a set of switch contacts, a member connected to open and close said switch contacts, spring means for normally holding said member and said pressure responsive means in direct unitary operative connection to cause the member and the pressure responsive means to normally operate as a unit responsive to pressures, and manual operating means independent of said pressure responsive means and acting directly upon said member for opening said contacts.

65 3. A control switch including a pressure responsive means, a set of switch contacts, snap acting means for opening and closing said switch contacts with a snap action, a member connected to said snap acting means to open and close said 70 switch contacts through the interconnection of the snap acting means, spring means for normally holding said member and said pressure responsive means in direct unitary operative connection to operate said member responsively to 75 changes in pressure, and manual operating means

independent of said pressure responsive means and acting directly upon said member to open said contacts.

4. A snap acting switch means including a primary operating member, a secondary member pivoted to the primary member, a pivotally mounted switch contact member, said switch contact member extending in the opposite direction from the pivot from that of the secondary member, spring means connecting the free ends 10 of said switch contact member and said secondary member, abutment means for limiting the movement of the free end of said secondary member, said secondary member and said switch contact member being tripped when the pivot of 15 the secondary member crosses the center line of the spring means, cushioning means for silencing the contact of the secondary member with the abutment member when the secondary member is tripped, and means independent of the 20 cushioning means for holding the free end of said secondary member in proper position immediately before tripping.

5. A snap acting switch means including a 25 primary operating member, a secondary member comprising a flat U-shaped piece of sheet metal, the two legs of said sheet metal being formed with knife edges which rest against a portion of said primary operating member forming a pivot, a pivoted switch contact member, said switch contact member extending from its pivot in a direction opposite to that in which the secondary member extends from its pivot, a coil spring connecting the free ends of the secondary member and said contact member, said coil 30 spring holding said knife edges of said secondary member against the portion of the primary operating member, and abutment means for limiting the movement of the free end of said secondary member.

40 6. A snap acting switch means including a primary operating member, a secondary member pivoted to said primary member, supporting means, a switch contact member pivoted to said supporting means, spring means connecting said 45 secondary member and said switch contact member, said stationary means having means for limiting the movement of the free end of said secondary member, said secondary member and said spring contact member being tripped when 50 the pivot of said secondary member crosses the center-line of the spring means, cushioning means for silencing the contact of the secondary member with the stationary means, said stationary means having means independent of the 55 cushioning means for holding the free end of said secondary member in proper position immediately before tripping.

7. A control switch including an electric circuit, pressure responsive means for opening and closing said electric circuit in accordance with changes in pressure, overload means for opening the circuit under predetermined current conditions, manually operable means for selectively varying the operation of said pressure responsive 65 means including a hollow shaft having manually rotatable dial means connected thereto, and means extending through said hollow shaft for resetting said overload means after the circuit has been opened by the overload means.

70 8. A control switch including an electric circuit, pressure responsive means for opening and closing said electric circuit in accordance with changes in pressure, overload means for opening the circuit under predetermined current con- 75

ditions, manually operable means for selectively varying the operation of said pressure responsive means including a hollow shaft having manually rotatable dial means, connected thereto, and means extending through said hollow shaft having an end portion extending therefrom for indicating that the overload means has opened the electric circuit.

9. A control mechanism including a member to be operated, a pressure responsive means, adjustable spring means acting upon said pressure responsive means for controlling the operation of said pressure responsive means, an operating arm connected to operate said member to be operated, resilient means for connecting said pressure responsive means and said operating arm for normally causing said operating arm to move responsive to movements of said pressure responsive means, manual control means for selectively controlling said spring means and said operating arm, said manual control means having a plurality of selective positions, means controlled by said manual control means when in one of said selective positions for varying the tension of said adjustable spring means, and means controlled by said manual control means when in another operative position for positively controlling said operating arm independently of the movement of said pressure responsive means.

10. A switch including means for opening and closing an electric circuit, a movable element for operating said circuit opening and closing means, a range adjusting means for modifying the opening and closing points of the switch with the differential between the starting and stopping points remaining the same, a differential adjusting means for controlling the differential between opening and closing points, and a common manual control member for changing the adjustment of both the range adjusting means and the differential adjusting means.

11. Control apparatus comprising an adjustable member movable in response to variations in value of a controlling factor between minimum and maximum limits thereof, and means for automatically restricting and widening said limits in response to adjustment of said member to accommodate changes in conditions affecting said controlling factor.

12. Control mechanism comprising, in combination, means movable in response to variations in one of the factors effecting the control, adjustable spring means resisting said movement, supplemental spring means also resisting said movement, and means for simultaneously adjusting both of said spring means to vary the effect thereof.

13. In a thermally actuatable switch construction, a switch having a movable switch member, a thermostat associated with the switch member exerting force tending to move the switch in switch closing direction in accordance with thermostat temperatures, opposing yieldable means comprising a pair of yieldable elements disposed to oppose thermostat actuated movement of the switch member in switch closing direction and to assist movement thereof in the switch opening direction, the thermostat effecting closing of the switch at a predetermined relatively high temperature only and one of the yieldable elements effecting opening of the switch at a predetermined relatively lower temperature, adjusting means comprising an adjustably movable member movable through a range of movement, transmitting means for transmitting movement of the mov-

able member to the yieldable elements, the transmitting means being responsive to vary the effectiveness of the first mentioned yieldable element to change the predetermined switch closing and opening temperatures at substantially the same rate through a part of the range of movement of the movable member, and through another part of its range responsive to change the effectiveness of the other yieldable element to change the predetermined closing temperature.

14. In a thermally actuatable switch construction, a switch having a movable switch member, a thermostat associated with the switch member exerting force tending to move the switch in closing direction in accordance with thermostat temperatures, a plurality of yieldable elements disposed to oppose thermostat actuated movement of the switch member, the thermostat effecting closing of the switch at a predetermined relatively high temperature only, and the yieldable elements effecting opening of the switch at a predetermined relatively lower temperature, adjusting means comprising an adjustably movable member movable through a range of movement, transmitting means for transmitting movement of the movable member to one of the yieldable elements and responsive to adjustably change the effectiveness thereof to change the predetermined switch closing and opening temperatures at substantially the same rate through a part of the movement range of the movable member, and through another part of its range, responsive to change the effectiveness of another yieldable element to change the predetermined closing temperature at a greater rate than the opening temperature.

15. In a thermally actuatable switch construction, a switch having a movable switch member, a thermostat associated with the switch member exerting force tending to move the switch in closing direction in accordance with thermostat temperatures, a plurality of yieldable elements disposed to oppose thermostat actuated movement of the switch member, the thermostat effecting closing of the switch at a predetermined relatively high temperature only, and the yieldable elements effecting opening of the switch at a predetermined relatively lower temperature, adjusting means comprising an adjustably movable member movable through a range of movement, transmitting means for transmitting movement of the movable member to one of the yieldable elements and responsive to adjustably change the effectiveness thereof to change the predetermined switch closing and opening temperatures substantially without changing the temperature difference, through a part of the range of movement of the movable member, and through another part responsive to change the predetermined closing and opening temperatures and the temperature difference therebetween.

16. In a thermally actuatable switch construction, a switch having a movable switch member, a thermostat associated with the switch member exerting force tending to move the switch in closing direction in accordance with thermostat temperatures, a plurality of yieldable elements disposed to oppose thermostat actuated movement of the switch member, the thermostat effecting closing of the switch at a predetermined relatively high temperature only, and the yieldable elements effecting opening of the switch at a predetermined relatively lower temperature, adjusting means comprising an adjustably movable member movable through a range of movement, trans-

- mitting means for transmitting movement of the movable member to one of the yieldable elements and responsive to adjustably change the effectiveness thereof to change the predetermined switch closing and opening temperatures substantially without changing the temperature difference therebetween, through a part of the range of movement of the movable member, and through another part responsive to change the predetermined closing and opening temperatures, and to increase the temperature difference therebetween.
17. In a thermally actuatable switch construction, a switch having a movable switch member, a thermostat associated with the switch member exerting force tending to move the switch in closing direction in accordance with thermostat temperatures, a plurality of yieldable elements disposed to oppose thermostat actuated movement of the switch member, the thermostat effecting closing of the switch at a predetermined relatively high temperature only, and the yieldable elements effecting opening of the switch at a predetermined relatively lower temperature, providing a temperature difference therebetween, adjusting means comprising an adjustably movable member movable through a range of movement, transmitting means for transmitting movement of the movable member to one of the yieldable elements and responsive to adjustably change the effectiveness thereof to change the predetermined switch opening temperature by substantially equal amounts for equal amounts of movement of the movable member over its entire range of movement, and responsive to change the predetermined closing temperature by substantially equal amounts for equal movements of the movable member over a part of its range and by greater amounts for equal movements over another part of its range.

18. In an automatic refrigerator, a controller for maintaining the temperature or pressure at a selected place within predetermined limits, comprising a casing, temperature or pressure sensitive means within said casing responsive to changes in the temperature or pressure at the place under control, variably resilient means for selectively predetermining the range of the limits of temperature or pressure maintained by the controller from a low temperature range to the defrosting range, a switch device associated with

said sensitive means to be operated thereby when the limiting temperatures or pressures are reached, and manually operable means located externally of the casing and cooperatively associated with said sensitive means to vary the differential of the limiting temperatures or pressures maintained by the controller in a manner to cause increase of the closed periods of the switch over the normal periods determined by the resilient means as the range is raised, whereby increased refrigerating periods are obtained at the defrosting range and a food-preserving temperature is maintained in the refrigerator during defrosting.

19. A control switch including an electric circuit, temperature responsive means for opening and closing said electric circuit in accordance with changes in temperature, manually operable means for controlling the operation of said switch including a hollow shaft member and a member extending through said hollow shaft member, a range adjustment means for varying the average operating temperature of said switch, an auxiliary control for said switch, and means for connecting one of said members to said range adjustment means and the other member to said auxiliary control.

20. A snap acting switch means including a toggle means, a set of contacts operated by said toggle means, operating means for said toggle means, cushioning means for stopping the toggle means at one end of its movement, and durable accurate locating means independent of said cushioning means for accurately locating the movable portion of the toggle means immediately prior to tripping for insuring accuracy of the tripping point of the toggle means.

21. A switch including means for opening and closing an electric circuit, a movable element for operating said circuit opening and closing means, a range adjusting means for modifying the opening and closing points of the switch remaining the same, a differential spring for controlling the differential between opening and closing points, adjusting means for adjusting the tension of the differential spring and a common manual control member for changing the adjustment of the range adjusting means and the tension of the differential spring.

GEORGE C. PEARCE. 50
